UNITED STATES PATENT OFFICE.

HARVEY A. SELLERS, OF DECATUR, ILLINOIS.

KITE.

Application filed November 14, 1921. Serial No. 514,872.

To all whom it may concern:

Be it known that I, HARVEY A. SELLERS, a citizen of the United States, a resident of Decatur, in the county of Macon and State of Illinois, have invented new and useful Improvements in Kites, of which the following is a specification.

This invention has reference to kites, particularly of the knock-down type, and has for its principal object to improve the strut structure thereof.

A further object of the invention is to provide a flexible binder, preferably a rubber band, to hold the struts when in knock-down relation and wrapped in the body of the kite when stored or being shipped.

The invention has for a further object to slit the ends of the struts parallel with the kite body, when receiving the string forming the selvage for said body; the length of the struts relative to the distance across the kite body to the points of intersection with the string being such, that the struts are slightly buckled when assembling the kite so as to put a tension on the string and thereby hold the body taut across the strut structure.

That the invention may be more fully understood, reference is had to the accompanying drawings, forming a part of the description, illustrating a preferred embodiment of the invention, in which:

Figure 1 is a rear face view of a kite embodying my invention;

Figure 2 is a detail of a corner of the kite, showing the selvage string and the strut engaging the same, and

Figure 3 is a perspective view of the struts knocked-down and assembled for storage or shipping and with the flexible binder holding the same together.

Like characters of reference denote corresponding parts throughout the figures.

I am aware that it is not broadly new to provide a knock-down kite, having a folding strut structure, with the ends of the struts slotted so as to be connected at the corners of the kite with a selvage string. Such as I am aware of, however, the struts are connected by a pivot pin, which adds considerably to the cost, both in material and labor and more particularly the latter, and if the boy or girl using the kite breaks a strut the pin must be removed with the danger of splitting one or the other of the remaining struts. Further, such kites as I

am familiar with the ends of the struts are slotted in a direction transverse to the flat side of the body of the kite requiring knotted ends connected to the selvage string to be slipped into such notches. This also adds to the cost, because of additional material and labor.

Kites such as herein disclosed are used by children and they must be manufactured at the least possible cost, so as to be retailed cheaply and so constructed that they may be easily and quickly assembled and knocked-down and rolled up.

While I have shown and prefer to use a flexible binder, such as a rubber band to bind the struts when knocked-down and which yieldingly holds the struts at their crossing point when the kite is assembled, it will be apparent that when the struts are caused to engage the selvage string and tension applied thereto a binder at their crossing point may be dispensed with.

Referring now to my improved kite, which is preferably of the six-sided type, 1 designates the body made of paper or other suitable material. 2 is a selvage string secured within the turned edges 3 which are pasted down in the usual manner. The selvage string 2 being exposed at the corners of the kite, as shown, by cutting away the corners with V shaped notches 4.

The struts, of which there are preferably three, are designated 5. When knocked-down, as shown in Figure 3 they are laid one upon the other and a binder, such as a rubber band 6 used to bind them. When so arranged they may be laid diagonally across the body 1 of the kite and rolled therein for storage or shipping. The binder 6 may also serve to yieldingly hold the struts in their crossing relation, when the kite is assembled, as in Figure 1, although this is not entirely necessary. The ends of each strut is provided with a slit 7 in the end thereof to engage and receive the selvage string, as shown in Figures 1 and 2. I prefer to slit the ends of the struts, so that said slits, when the struts are laid on the body 1 lie parallel to the surface of said body and in the plane of the selvage string. In this manner the ends of the struts may engage directly with the selvage string, without the necessity of providing separate engaging strings, or knotting the selvage string so as to provide engaging ends.

I also provide the struts in such lengths,

relative to the distance across the kite from one engaging corner to the other, that they should be buckled slightly to engage the selvage string and put the same under tension, and thereby secure the body 1 taut across the strut structure.

What I claim is:—

In a kite, in combination, a frame comprising a plurality of sticks adapted to have 10 a radiating crossing relation, a six sided foldable covering for said frame cut away V shape at the corners and having a single cord binder exposed at the cut away cor-

ners; said sticks being of such a length relative to the distance between the corners of the kite as to require the buckling of said sticks to engage said cord binder and each end of the sticks having a slit to receive said binder cord, and a non-removable elastic and flexible binder to hold the sticks 20 when knocked down and at their crossing point when the kite is assembled.

In witness whereof, I have hereunto affixed my hand this 5th day of November, 1921.

HARVEY A. SELLERS.
